Primary Examiner — Celia Murphy*Assistant Examiner* — Clare Ann Gannon(74) *Attorney, Agent, or Firm* — Thompson Coburn LLP(57) **CLAIM**

The ornamental design for a shoe, as shown and described.

DESCRIPTION

FIG. 1 is a perspective view of a shoe showing our new design;

FIG. 2 is a top plan view thereof;

FIG. 3 is a lateral side view thereof;

FIG. 4 is a medial side view thereof;

FIG. 5 is a front view thereof;

FIG. 6 is a rear view thereof; and,

FIG. 7 is a bottom plan view thereof.

The broken lines depicting the tongue, heel pull-strap, eyelets, and inside surfaces of the shoe form no part of the claimed design.

1 Claim, 6 Drawing Sheets(56)
